OIL VAPORIZER CONTROL

Clyde B. Faverty, Chicago, Ill., assignor, by mesne assignments, to Mark C. Bates, Chicago, Ill.

Application February 12, 1934, Serial No. 710,971

19 Claims. (Cl. 158—53)

My invention relates in general to oil vaporizing and burning mechanism. It relates more in particular to control means for a vaporizer by means of which more accurate burner control and the like is obtained.

Those skilled in the art are referred to the copending application of C. A. French, Serial No. 603,491 filed April 6, 1932 wherein apparatus is shown for vaporizing a liquid hydrocarbon such as "gas oil". The French vaporizer is of considerable utility particularly in certain industries for supplying a gas of a sufficiently stable character to permit its being piped short distances to industrial furnaces and ovens. For this reason, the equipment can be used to take the place of gas in industries where a close control of temperature and furnace atmosphere is necessary. Considerable saving results from its use. Certain disadvantages and objections, however, arise when the French equipment is used under certain conditions. For example, if a single vaporizing unit is employed to supply a combustible mixture to a plurality of furnaces or ovens, a problem has arisen in that when the combustible mixture is shut off to one burner, there is a tendency to supply an excessive amount of the combustible mixture to the remaining burners. So also, when the equipment is adjusted to supply less than the number of burners present, when additional burners are turned on there is a tendency for the supply of combustible mixture to the plurality of burners to be insufficient to maintain temperature. Additional problems arise in connection with maintaining the proper relative mixture of air and vaporized hydrocarbon when a plurality of burners is supplied. Other problems in control are encountered, but in general the case of the use of a plurality of burners is typical and sufficiently illustrative.

The principal object of my present invention is the solution of the problem indicated.

Another object is to provide an automatic control for vaporizing apparatus when the same is connected to supply a plurality of burners.

Still another object is the provision of improved vaporizing structure whereby pilot burner operation and operation of the vaporizer as a whole are enhanced.

Another object is the provision of an improved diaphragm control mechanism for regulating the supply of air to the vaporizing apparatus.

A further object is to maintain a substantially constant pressure in a manifold between an oil vaporizing apparatus and a burner.

A still further object is to maintain a substan-

tially uniform mixture of air and oil vapor in a manifold whether the vaporizing apparatus is operating at maximum capacity or short of maximum capacity.

A further object is the provision of simple means for raising or lowering an established manifold pressure to suit variable operating requirements.

Another object is to control the output of a vaporizer in response to manifold pressure.

Still another object is to amplify the manifold pressure variation by means of pressure from a separate source.

I show and shall describe certain embodiments of my invention in connection with the French type of vaporizer heretofore referred to in describing problems sometimes arising in the use of this general type of equipment. It will be evident to those skilled in the art that the invention may be used with many types of installations. It is particularly adapted, however, for use when a French type of vaporizer is used to supply a plurality of burners placed in different ovens or furnaces, each separately controlled as to temperature and operation.

According to the main features of the present invention, I employ a diaphragm type of vaporizer control responsive to changes in manifold pressure so arranged that if one or more burners are extinguished or turned down, the amount of air and vapor delivered to the manifold is decreased, while the same proportions thereof are maintained. When a burner is turned on, the amount of air and vapor is automatically increased. Preferably I use a pilot control so that air under pressure, controlled by the pilot, furnishes the operating pressure.

On the French type of vaporizer, a tapered metering rod is movable axially of a forcing nozzle forming a part of an inspirator which draws oil vapor from a vaporizing chamber. The volume of air through the forcing nozzle is thus cut down without decreasing the velocity or impairing the suction on the vaporizing chamber. Co-incidentally with the operation of the metering rod, a valve is actuated to control the vapor passageway to the inspirator, and assists in maintaining a uniform air-vapor mixture.

Other objects and features of the invention will be apparent from a consideration of the following detailed description taken with the accompanying drawings, wherein

Fig. 1 is an elevational view, partly in section, showing the features of the vaporizing apparatus and control therefor;

Fig. 1a illustrates more or less schematically a group of burners or ovens, the scale being made smaller than used in Fig. 1;

Fig. 2 is an enlarged vertical sectional view taken through part of the control mechanism of Fig. 1;

Fig. 3 is a sectional view taken on the line 3—3 of Fig. 1;

Fig. 4 is a modification of the control apparatus shown in Fig. 1, wherein only a single diaphragm valve is employed; and

Fig. 5 illustrates still another modification in which control is based upon a different principle.

Now considering the details of the invention, I shall refer first to the general features of the vaporizer illustrated in Fig. 1 and thereafter shall describe the control means therefor. Air under pressure is supplied from a blower, air pump, or suitable mechanism 8 to an air delivery pipe 10, whence it is delivered to an inspirator including a forcing nozzle 11 and a Venturi mixing nozzle 12. An annular passageway or gas distributing chamber 13 between the forcing nozzle and the mixing nozzle connects with a vapor passageway 14 controlled in part by a butterfly type of valve 16. The passageway 14 is connected to a vaporizing chamber 17 where a constant level of liquid hydrocarbon is maintained by a float valve mechanism 18. The vaporized hydrocarbon or gas is accordingly drawn through the passageway 14, combines with air as it passes through the mixing nozzle 12 to form a combustible mixture and is delivered through a larger passageway 19 connected to and forming a part 35 of a manifold 21. The float valve mechanism 18 is provided with a pipe 18a which is connected with the vaporizing chamber 17 whereby equal pressure conditions are maintained in both the float chamber and the vaporizing chamber. 40 A pipe 18b connects the float chamber with the lower part of the vaporizing chamber 17 to provide for the passage of the liquid hydrocarbon into said vaporizing chamber.

The passageway 19 is constructed in the form 45 of a casting in which is provided a trap 22 for withdrawing some of the combustible mixture and supplying the same through a pipe 23 to a pilot burner indicated generally by the character 24. The mixture is burned and passes downwardly through a vertical passageway 26. The integral passageway 26 is provided with an extension 27 carrying a bubble plate 28 disposed beneath the level of the liquid. Here the hot gases of combustion are broken up and pass upwardly through a plurality of openings in the bubble plate. In passing through the liquid hydrocarbon, the hot gases vaporize a portion of this liquid, and the vaporized portion with the burned gases are drawn through the passageway 55 14 into the Venturi tube 12. This is the cycle of operation, it being understood, of course, that the major portion of the combustible mixture passes to the manifold 21 where it is available for burning at a plurality of burners provided in 60 ovens 29—29.

It will be noted that the casting is constructed so that the trap opening 22 is positioned sufficiently above the lower inside surface thereof so that any vaporized liquid which might condense in the large passageway 19 cannot find its way into the pilot burner. At a suitable place in the manifold, I also provide a trap 31 for catching any condensate that may form in this place. The trap is connected by a pipe system 75 32 to the vaporizing chamber 17, so that what-

ever condensate is formed is returned directly to the system.

Inserted in the gas passageway to the pilot tube I provide a valve system including a butterfly type of valve 33 controlled by a handle 34, with a calibrated segment to show the position of the butterfly valve and stops 36 which can be set to limit the movement thereof. By this means I can set the butterfly valve to produce any suitable and selected type of flame at the pilot burner.

The burner 24 is of special construction to avoid the possibility of having the flame thereof extinguished due to high velocity of the gas passing therethrough. To this end it is provided with a central burner opening 37 and relatively smaller radially disposed openings 38. A hood 39 is positioned in front of the openings 37 and 38, this hood being of generally tubular cross-section but flanged at the forward end to provide a large but relatively restricted opening 41 through which the flame passes. It will be noted that the burning gases passing through the opening 37 are directed centrally through the opening 41. The small radial openings 38, however, are directed to strike against the inside surface of the hood 39 where the flame therefrom is caused to converge toward the center by reason of the flanged forward end of this hood. In this manner, relatively small portions of flame or burning gases are directed inwardly against the main body of burning gas and keep the main body of gas ignited at all times. The small flames at the openings or ports 38 are maintained partly because the gas passing therethrough is restricted in velocity and partly because the hood 39 is maintained at a relatively higher temperature and assists in keeping the relatively smaller flames from being extinguished. Immediately in advance of the pilot burner, I provide a tubular insert 42 of heat resisting material such as a high grade of alloy steel. The burner itself may also be formed of the same or similar material. A housing 43 is provided around the entire burner structure equipped with a handle 44 by means of which the housing can be moved to the right to clean or inspect the burner.

The principal control feature includes a pair of diaphragms, one operating to move air volume control mechanism and the other operating to control a supply of air to the first mentioned diaphragm, this second mentioned diaphragm being controlled by the gas pressure within the manifold. I shall first describe the means for controlling the volume of air delivered to the apparatus.

The main air delivery pipe 10 is provided with a specially designed elbow fitted with a rear boss 46, giving the elbow the appearance generally of a T. Within the boss 46 is supported an apertured plug 47 in which a metering rod 48 is slidably secured. This sliding rod has a tapered portion 49 adapted to be extended into the forcing nozzle 11 to partially close the same. In advance of the tapered portion is a relatively small diameter extension 51 doweled on the center line of an apertured plate 52 carried between the Venturi tube 12 and the casing 19. By forming the plug 47 and the apertured plate 52 to close dimensions, the rod 48 and the tapered portion 49 thereof can be carried substantially exactly on the center line of the opening in the forcing nozzle 11. I construct the rod 48 so that if the tapered portion thereof is extended entirely through the forcing nozzle, a very small annular opening will re-

main for the passage of air therethrough. I have found that an opening of the order of a sixtieth to a thirty-second of an inch gives very suitable results when the vaporizer is of a capacity to supply four or five burners. This will permit all but one of the burners to be extinguished and a proper mixture still delivered to the remaining single burner; while the vaporizer will be of sufficient capacity to deliver a suitable combustible mixture to the four or five burners when they are in full operation.

The rod 48 is provided with a pivoted extension 52 pivoted to a lever arm 53 fulcrumed at 54 to a stationary extension 56 supported by suitable frame structure. A tension spring 57 connects the lower end of the lever arm 53 tending to hold the rod 48 at the extreme left or entirely out of the forcing nozzle passageway. Slightly below the pivot, the lever arm 53 is pivoted to a stud 58 secured to a diaphragm 59. This diaphragm is supported within a bi-part diaphragm casing 61. It is obvious that if air under pressure is delivered to the diaphragm casing at the right side of the diaphragm looking at Fig. 1, and this air pressure is sufficient to overcome the force of the spring 57, the rod 48 will be forced to the right through the lever arm connections shown and the amount of air passing through the forcing nozzle and consequently the amount of combustible mixture delivered to the burners will be decreased. I may place the manifold 21 directly in contact with the diaphragm 59 to secure direct control such as that which I show in Fig. 4 and which will afterward be described. In order to secure a more dependable operation, however, I employ a second diaphragm as an intermediate control, as will now be shown.

The intermediate control comprises a diaphragm 62 supported in a bi-part casing 63. One side of the diaphragm is in communication with the manifold through a pipe 64. At the opposite side of the diaphragm I provide a valve consisting of a valve seat 66 and a poppet type of valve 67 provided with a valve stem 68 slidably supported in the valve housing 69 of which the seat forms a part. A compression spring 71 has one end bearing against the valve 67 and the opposite end bearing against one end of a cup-shaped spring housing 72. This spring housing is threaded in the valve housing 69 so that the compression of the spring 71 can be controlled by the position of the spring housing. One side of the valve is connected by a pipe 73 to the main air pipe 10 and the other side thereof is connected by a pipe 74 to one side of the diaphragm 59. A small bleeder passageway 76 is provided in the pipe 74 to permit return of the diaphragm when valve 67 is closed.

For further control, an arm 77 is secured to the butterfly valve 16. This arm is provided with a plurality of openings for adjustably attaching thereto to a rod 78 pivoted to the lever 53. This rod is shaped as shown to pass over the diaphragm casing 61 without obstruction.

In the operation of this mechanism, the vaporizing chamber is first heated up in any suitable way and then oil is admitted thereto at a level controlled by the float mechanism 18. The blower supplying air to the pipe 10 is now operated, and there will be some vapor drawn from the chamber 17, usually sufficient to start the operation of the pilot burner. In cold weather, or to secure rapid starting, it may be advisable to hold a blow torch at the pilot light opening by first withdrawing the covering or shield 43.

During the time of starting, it may be advisable to disconnect the rod 78 from the arm 77 to allow the butterfly valve 16 to be held completely open. When the pilot burner is first operated, it may also be necessary to hold the butterfly valve 16 completely open. By these and other means the vaporizer is brought up to full operating condition and the combustible mixture produced thereby is delivered to the burners of the furnaces or ovens 29. The spring 71 is set to the desired maximum requirements for the number of burners used so that when the maximum output of gas desired is being consumed, the valve 67 will be held against its seat. Assume now that less than the entire number of burners is being operated. A slight pressure increase will result in the manifold and this will operate the diaphragm 62 and partially open the valve 67 against the action of spring 71. This admits air from the pipe 10 to the right hand side of diaphragm 59. This diaphragm is then forced to the left, resulting in the rod 48 being moved slightly toward the right to partially close the opening of the forcing nozzle 11. At the same time, the arm 77 is moved to partially close the butterfly valve 16. This automatically decreases the amount of combustible mixture delivered to the manifold. If now another burner is lighted, the opposite effect will take place and the amount of combustible mixture delivered to the manifold will be increased. It will be understood, of course, that this action takes place quickly and more or less constantly during the operation of a battery of furnaces or ovens. Usually the burners supplying heat to such furnaces or other containers are thermostatically controlled. The control mechanism described co-operates and functions with automatic control of the burners and maintains substantially the exact amount of combustible mixture desired at any particular setting of the burners. By means of the present control, particularly with thermostatic control means for the burners, I have been able to maintain furnaces, ovens and other heating plants such as kilns and the like at a substantially uniform pressure, varying not more than a few degrees either side of the desired setting under the most unfavorable conditions.

In connection with the equipment shown, it is at once apparent that all of the parts thereof are readily accessible for repair and/or replacement, and are simple and readily kept in order and adjustment. I find that it is desirable to clean the metering rod 48 occasionally and to this end the lever arm 53 is bifurcated at the top and the rod extension is pinned between the bifurcations as shown particularly in Fig. 3. This permits removal of the pin and the direct withdrawal of the rod 48 without disturbing any other part of the mechanism or changing the adjustment thereof.

Fig. 4 shows a rather simple modification of the principle shown in Fig. 1. The rod 148 is supported at only one point and is provided with a relatively long taper of the character shown. Other portions of the equipment that are the same as shown in Fig. 1 are given the same reference characters prefixed with the numeral "1" to facilitate and shorten the description. It will be noted that the pilot burner 124 is of somewhat modified construction with a hot point 81 for assisting in keeping the burner lighted. The hot point 81 comprises a pair of wires which become heated by the pilot flame and thereby assist in keeping the pilot burner lighted.

In this case I provide only a single diaphragm 82 in a diaphragm casing 83. A single lever 84 is pivoted intermediate its ends and is attached to diaphragm 82 in the manner shown. The 5 spring 157 serves to hold the rod 148 to the left. The pipe 164 communicates directly between the manifold and the diaphragm 82. When the pressure in the manifold increases, the diaphragm is moved directly to the left as a result of such 10 increased pressure, and operates directly to move the rod 148. The reverse action takes place in the same manner. While the specific mechanism shown in Fig. 4 will operate satisfactorily under most conditions, I find that in general the control is somewhat more accurate when the preferred form is used. On exceptionally large installations also employing large vaporizing units, I find that the pressure in the manifold is not sufficient as a rule to obtain quick control response when the burners are turned off and on. For relatively small installations, and particularly where a greater variation of temperature is permitted, the simplified form of Fig. 4 is thoroughly satisfactory.

25 In Fig. 5 I show still another modification adopted to be used principally when the vaporizing apparatus is operating the burners of only a single furnace or oven. This modified apparatus however may be used in other ways. In Fig. 5 30 I also employ the same reference characters employed in the previous figures with the prefix "1" for indicating that a modification is shown. The particular portions of the previously shown apparatus of interest in the present connection are 35 the diaphragm 182, the lever arm 184, the rod 148 which may be shaped substantially as shown in Fig. 4, and the spring 157 tending to withdraw the rod from the forcing nozzle.

In the modification of Fig. 5 I use a thermo- 40 static control directly. An expansible element 86, which may be in the form of a rod, is carried in a suitable position where it is affected directly by the heat resulting from burning the vaporized mixture. A suitable or usual position is within 45 the oven which is being controlled. This expansible member carries a valve 87 which is adapted to engage a valve seat 88. One side of the valve seat body communicates with the atmosphere while the other side thereof communicates with 50 a pipe 89 connected through a restricted passageway 91 and a forcing nozzle 92 to the main air supply pipe 110. This arrangement of the forcing nozzle 92 and the restricted passageway 91 creates a suction at this point and is connected by 55 a pipe 93 to the diaphragm casing 183 and the diaphragm 182.

The operation of this mechanism is as follows: The entire apparatus being set to the temperature desired, it will be assumed that the element 86 has been expanded to such a point that the valve 87 has engaged its seat 88 and prevented the passage of air therethrough. The air under pressure in pipe 110 will now cause a pressure to exist on the right hand side of the diaphragm 182 and this will operate the lever arm 184 against the action of spring 157 and move the rod 148 in a direction to shut off the air and decrease the amount of gas or combustible mixture delivered to the burner of the furnace or oven carrying the element 86. Assume now that this oven or furnace has its temperature lowered. The expansible member 86 will contract, the valve 87 will be removed from its seat and air is now permitted to pass therethrough. The result is 70 that the air from the forcing nozzle 92 can now

pass through the pipe 89. It will create a suction of a character determined by the velocity through the restricted portion 91. The air adjacent the diaphragm 182 being under pressure at this time and a partial suction being created at pipe 89, the diaphragm will immediately return to normal and the rod 148 will be withdrawn.

A feature of the operation of my invention is the provision of simple means for raising or lowering an established manifold pressure to suit varying operating requirements. For example, it may be assumed that in ordinary operation, a four-inch manifold pressure is to be maintained. For starting a furnace cold, however, it may be advisable to raise the manifold pressure to force 1 the furnace burner. The tension of spring 11 can then be increased by turning the adjustable housing 12 to the right. In this way, the manifold pressure may be increased to, say, five inches. Under other conditions, the pressure of spring 2 11 can be decreased and the manifold pressure can be reduced to, say, three or three and one-half inches. Some regulation can be made by controlling the tension of spring 87, but in general this adjustment is not so suitable, not so satisfactory, and not so readily controlled.

It will be understood that the invention is not limited by the specific arrangement thereof shown nor by the detailed language employed in the description thereof. Nor is it limited in its use with the specific type of vaporizing mechanism shown. It may be used wherever a constant manifold pressure is desired to be maintained and wherein a mixture of air and vapor of uniform quality is desired under all operating conditions.

Moreover, the term "manifold" as employed in the specification and particularly in the claims is used in a descriptive but not a restricted sense to include any portion of the passageway between the mixing nozzle and the burner.

The invention is explained as applied to the situation where a plurality of separately controlled burners is provided. It may be used in any analogous or equivalent situation in which a variable demand is made on a vaporizing apparatus. A simple example is a single burner or group of burners variably controlled to regulate the temperature of an oven or furnace. In this connection, it is to be noted also that the invention can be applied in an installation in which gas is substituted for a hydrocarbon vapor. The term "vapor" therefore is used in a broad sense.

What I claim as new and desire to protect by Letters Patent of the United States is:

1. In oil vaporizing apparatus, oil vaporizing means, a manifold, means for combining the oil vapor with air and delivering the resulting mixture to said manifold, means responsive to the pressure within the manifold for controlling the amount of air and vapor mixture delivered thereto, said means including a diaphragm controlled mechanism actuated by air delivered by air supply mechanism, a valve for controlling the air delivered thereto, and a second diaphragm control mechanism, said second mentioned diaphragm control mechanism actuating said air controlling valve.

2. In oil vaporizing apparatus including an oil vaporizing chamber adapted to contain a supply of liquid oil, an inspirator including a forcing nozzle, means for delivering air to the forcing nozzle, a connection with the vaporizing chamber and said inspirator at said forcing nozzle to draw vapor therefrom and mix the same with said air, a manifold for receiving said air and

vapor mixture and a plurality of burners connected with said manifold, separate means for burning a portion of said mixture and passing the hot gases resulting from the combustion of said portion below the level of liquid in the vaporizing chamber, and means responsive to pressure of the mixture within the manifold for controlling the amount of air passing through said forcing nozzle without substantially affecting the velocity thereof.

3. In oil burning apparatus, oil vaporizing means, means for delivering air under pressure and mixing the same with vaporized oil, a manifold for delivering the mixture to a burner, a control mechanism for regulating the amount of air delivered, an air control diaphragm for operating said air control means, a second diaphragm controlled by pressure within said manifold, and a valve controlled by said second mentioned diaphragm for controlling the amount of air delivered against said first mentioned diaphragm.

4. In oil burning apparatus, an oil vaporizing chamber, an inspirator including a forcing nozzle connected to draw oil vapor from said chamber, means for delivering air at relatively high velocity to the forcing nozzle, a manifold receiving air and vapor mixture from the inspirator for delivery to a plurality of burners, and means responsive to pressure within said manifold for controlling the amount of air delivered through the forcing nozzle without substantially affecting the velocity thereof, said last mentioned means including area control means at the discharge end of the forcing nozzle.

5. In oil vaporizing apparatus, a vaporizing chamber, a manifold, an inspirator including a forcing nozzle and a mixing nozzle, a connection to the vaporizing chamber between the forcing nozzle and mixing nozzle, means for forcing air under pressure to the forcing nozzle whereby vapor is mixed therewith to form a combustible mixture and delivered to the manifold, a metering rod having a tapered portion extending axially through the forcing nozzle, a diaphragm having one side thereof in communication with said manifold, a spring normally urging said metering rod in a direction to increase the pressure in the manifold, and means actuated by movement of the diaphragm in response to increased manifold pressure for moving said metering rod to decrease the area of said forcing nozzle and decrease said manifold pressure.

6. In a device of the character described, an air compressor and means for delivering air therefrom, a vaporizer, an inspirator including a forcing nozzle receiving said air under pressure and a connection to the vaporizer whereby vapor is withdrawn therefrom and combined with said air, means for changing the cross sectional area of the forcing nozzle, a diaphragm control for said last mentioned means including a diaphragm urged by air from said compressor in one direction and by a spring in the opposite direction, a pilot valve for controlling delivery of air to the diaphragm, and means for opening and closing said pilot valve in response to the pressure of the air and vapor mixture, whereby a substantially constant pressure is maintained between said inspirator and a delivery point for said mixture.

7. A device as defined in claim 6, including bleeder means in communication with said diaphragm whereby to permit said spring to move the diaphragm in the event of sudden closing of said pilot valve.

8. In a fuel burning device wherein prelimi-

narily produced fuel vapors are mixed with air under pressure and delivered to a manifold for delivery to a plurality of burners, control apparatus comprising, means for regulating the amount of combustible mixture of fuel vapor and air delivered to the manifold, said means including means for regulating only the amount of fuel vapor delivered to the manifold, an air pressure operated device for actuating both of said means, and means operated in response to the pressure within said manifold for causing operation of said air pressure operated device.

9. In a fuel burning device wherein preliminarily produced fuel vapors are mixed with air under pressure and delivered to a manifold for delivery to a plurality of burners, control apparatus comprising, means for regulating the amount of combustible mixture of fuel vapor and air delivered to the manifold, said means including means for regulating only the amount of fuel vapor delivered to the manifold, an air pressure operated device for actuating both of said means, and a valve for supplying air to said device, and means controlled by the pressure within said manifold for operating said valve.

10. In a fuel burning device wherein preliminarily produced fuel vapors are mixed with air under pressure and delivered to a manifold for delivery to a plurality of burners, control apparatus comprising, means for regulating the amount of combustible mixture of fuel vapor and air delivered to the manifold, said means including means for regulating only the amount of fuel vapor delivered to the manifold, an air pressure operated device for actuating both of said means, a valve for supplying air to said device, actuating means operable by the pressure within said manifold for operating said valve, and adjustable means for regulating the effective pressure required for operating said actuating means.

11. In oil burning apparatus, an oil vaporizing chamber, means for vaporizing the oil, an inspirator including a forcing nozzle connected to said vaporizing chamber, means for forcing air under pressure through said forcing nozzle whereby oil vapors are withdrawn from said vaporizing chamber, a manifold connected to said forcing nozzle and leading to a plurality of burners, and control means, responsive to the pressure within the manifold, for regulating the amount of air and oil vapor delivered to said manifold without substantially affecting the velocity of the air passing through the forcing nozzle, said control means comprising area control means at the discharge end of the forcing nozzle.

12. The apparatus described in claim 11, including means for burning at least a portion of the mixture of air and oil vapors and utilizing the products of combustion thereof to vaporize additional amounts of the oil in the vaporizing chamber.

13. In oil vaporizing apparatus, oil vaporizing means, a manifold, a forcing nozzle through which air is delivered to said manifold, means for combining the oil vapor with said air and delivering the resulting mixture to said manifold, and area control means at the discharge end of the forcing nozzle, said last mentioned means including means responsive to the pressure within the manifold whereby the amount of air and vapor mixture delivered to said manifold is controlled while maintaining the velocity of the air at the discharge end of the forcing nozzle substantially constant.

14. In oil vaporizing and burning apparatus, an oil vaporizing chamber, an inspirator including a forcing nozzle positioned to draw vapor from said chamber, means for conducting air under pressure to said forcing nozzle, a manifold for delivering mixed air and vapor to a plurality of burners, and means for maintaining a substantially constant manifold pressure independently of the number of burners to which the mixture is being delivered, said last mentioned means including area control means at the discharge end of the forcing nozzle, the area control means being operated in response to pressure of the mixture within the manifold whereby the velocity of the air at the discharge end of the forcing nozzle is maintained substantially constant.

15. In oil burning apparatus, an oil vaporizing chamber, an inspirator including a forcing nozzle connected to draw oil vapor from said chamber, means for delivering air at relatively high velocity to the forcing nozzle, a valve for controlling the amount of vapor delivered to the inspirator at any air velocity controlled in accordance with the rate of flow of the air delivered to the forcing nozzle, a manifold receiving air and vapor mixture from the inspirator for delivery to a plurality of burners, area control means at the discharge end of the forcing nozzle for controlling the amount of air delivered to the forcing nozzle whereby the air velocity at the discharge end of the forcing nozzle is maintained substantially constant, and means responsive to pressure within said manifold for operating said area control means.

16. The structure defined in claim 13, including separate means for maintaining a uniform mixture of the air and vapor.

17. The structure defined in claim 13, wherein in the area control means comprises a rod disposed axially of the forcing nozzle and adapted to vary the area of the outlet opening of said forcing nozzle.

18. In oil vaporizing apparatus, a vaporizing chamber, a manifold, an inspirator including a forcing nozzle and a mixing nozzle, a connection to the vaporizing chamber between the forcing nozzle and mixing nozzle, means for delivering air under pressure to the forcing nozzle and mixing it with fuel vapor in said mixing nozzle to form a combustible mixture which is delivered to the manifold, a metering rod having a tapered portion extending axially through the forcing nozzle, and means responsive to the demand for combustible mixture placed upon the manifold for moving said metering rod and maintaining a substantially constant pressure within said manifold, the velocity of the air through the forcing nozzle being substantially constant whereby inspirating action even at low air volume is maintained.

19. In oil vaporizing apparatus, a vaporizing chamber, a manifold, an inspirator including a forcing nozzle and a mixing nozzle, a connection to the vaporizing chamber between the forcing nozzle and mixing nozzle, means for forcing air under pressure to the forcing nozzle and mixing it with fuel vapor in said mixing nozzle to form a combustible mixture which is delivered to the manifold, a metering rod having a tapered portion extending axially through the forcing nozzle, means responsive to the demand for combustible mixture placed upon the manifold for moving said metering rod and thereby maintaining a substantially constant pressure within said manifold, the velocity of the air through the forcing nozzle being substantially constant whereby inspirating action even at low air volume is maintained, a valve between the vaporizing chamber and said inspirator, and means for actuating said valve as an incident to the actuating of said metering rod whereby a substantially uniform mixture is maintained even at low volume.

CLYDE B. FAVERTY.
